Attorney

UNITED STATES PATENT OFFICE.

JOHN HAVRAN, OF BEDFORD, OHIO.

RAZOR-BLADE HOLDER.

Application filed June 1, 1926. Serial No. 113,053.

The present invention relates to holding devices for safety razor blades and the like, and has for its prime object to provide a holder of the above character which is 5 simple yet durable of construction and efficient in use.

Another object of the invention is the provision of a razor blade holder designed to permit rapid and secure attachment of the 10 blade at the correct angle for stropping thereof.

A still further object of the invention is the provision of a holder of the above type which may be readily adapted for stropping 15 various types of blades now on the market.

Still another object of the invention is the provision of a blade holder which will be convenient in application and which can be manufactured at a comparatively low cost.

20 In the accompanying drawings forming a part of this specification and in which like reference characters are employed to designate corresponding parts throughout the same:

25 Figure 1 is a side elevational view of my improved blade holder, showing a blade in operative position therein,

Figure 2 is a bottom plan view of the same,

30 Figure 3 is a partial transverse section showing the blade supporting plates in end elevation,

Figure 4 is an enlarged transverse sectional view taken on the line 4—4 of Figure 1,

35 Figure 5 is a side elevational view of one of the blade holding plates of the preferred form of my invention.

Figure 6 is a similar view of a complementary plate,

40 Figure 7 is a partial transverse section showing a modified form of the blade holding plates in end elevation,

Figure 8 is a side elevational view of a 45 plate employed in this modified form of structure,

Figure 9 is a side elevational view of a complementary plate,

Figure 10 is an enlarged transverse sectional view through a still further modified 50 form of structure,

Figure 11 is a side elevational view of one of the holding plates employed in this modified form, and

Figure 12 is a side elevational view of the 55 complementary plate employed in the last mentioned form.

Referring to the drawing, wherein for the purpose of illustration is shown a preferred and several modified forms of my invention, 60 the numeral 15 designates in its entirety the frame of my improved holder, the same being composed of a pair of longitudinal bars 16 preferably of metallic construction. These bars are secured in parallel spaced positions by means of a plurality of spacing blocks 17, formed of rectangular metallic blocks arranged at the ends of the bars and at the intermediate portion thereof. The bars and blocks are provided with aligned 65 openings and secured by rivets 18 or in any desirable manner. With particular reference to Figures 1 and 2 of the drawing, it will be noted that the intermediate block 17 is arranged somewhat adjacent the forward 70 end of the frame so as to provide a blade engaging portion at one end and a substantially longer handle portion at the opposite end.

Formed for resilient connection with the 75 blade holding portion of the frame 15 are a pair of complementary blade supporting plates 19 and 20. These plates are preferably constructed of sheet metal and have their upper edges bent in substantially U-shaped formation as at 21, the outer edges being inclined to provide a resilient gripping flange 22. These flanges 22 will overhang the upper edges of the frame bars to provide laterally extending bevel supports by 80 means of which the razor blade will be maintained in a proper angular position during the stropping operation. The lower longitudinal edges of the plates are beveled as at 23 to facilitate the movement of the holder 85 on the strop. The plate 19 is provided with a pair of openings 24 arranged in horizontal alinement and adapted to engage a pair of sleeves 25 carried by the complementary plate 20, as shown to advantage in Figure 4. 90

This type of blade holder is particularly adapted for stropping Gillette and similar razor blades, the intermediate portions of this type of blade being provided with a pair of spaced openings adapted to aline 95 with the openings 24 formed in the holding plate 19. The blade is first arranged upon the sleeves 25 carried by the plate 20 and the

complementary plate 19 then inserted over the end portions of the sleeves. The razor blade and holding plates are then placed in proper stropping position in the holding portion of the frame 15, the upper flanged edges of the plates being snugly fitted over the upper edges of the frame bars and held against displacement by the resilient structure of the holding flanges 22. Thus, the assembled device presents a structure of tapered, substantially V-shaped cross section for efficient sharpening of the blade. The blade may be then conveniently and efficiently sharpened by movement over the usual type of razor strop, in the same manner as the conventional straight razor. This will greatly prolong the usefulness of the blades and provide a sharper cutting edge so as to enhance the shaving quality thereof.

With particular reference to Figures 7, 8 and 9, wherein is shown a modified form of structure, the complementary holding plates 26 and 27 are similar in formation to the plates 19 and 20 in the preferred form of my invention. These blades embody U-shaped upper edge portions 28 having resilient angular flanges 29 for engagement with the holder frame. The lower edges of the plates 26 and 27 are beveled as at 30, while the plate 27 is provided with a pair of openings 31, spaced farther apart than in the preferred form of holding plates, for use in connection with the auto-strop and other blades of similar formation. The complementary plate 26 is provided with sleeves 32 arranged in transverse alinement with the openings 27 adapted to be inserted therein, these sleeves being arranged for engagement with the semicircular notches formed in the ends of this type of blade.

These holding plates and the blade are assembled in the frame 15 in the same manner as previously described for the preferred form and firmly hold the blade in position for stropping.

In order to accommodate safety razor blades of the Gem type, I provide a still further modified form of holding means including a pair of duplicate plates 33 bent at the upper ends as at 34 and having resilient side flanges 35. The intermediate portions of these plates have longitudinal slots 36 of generally rectangular formation arranged in opposed positions. These slots are formed to freely engage the reinforcing rib 37 of the Gem blade 38 so that when the holding plates are tightly inserted in the frame 15 the blade will be rigidly held in position.

From the foregoing description and the drawing, it will be readily seen that I have provided a simple and durable type of blade holder designed to accommodate various forms of safety razor blades. The particular formation of the device will permit

rapid connection and disconnection of the blades in the frame structure and greatly facilitate sharpening of the blades.

It is to be understood that the form of my invention herewith shown and described is to be taken as the preferred example of the same, and that various changes as to the size, shape and arrangement of parts may be resorted to without departing from the spirit of the invention or the scope of the subjoined claims.

Having thus described my invention, what I claim is:

1. A device of the character described comprising a frame including a pair of spaced bars, spacing blocks arranged between the bars, and means for securing the said bars and blocks together, a pair of complementary holding plates having their upper ends bent in U-shaped formation to provide outwardly arranged resilient flanges, one of the said plates being provided with a pair of spaced openings, and the opposite plate carrying transversely extending sleeves for engagement with the openings, the said sleeve and openings being arranged to engage a razor blade.

2. A blade holder of the class described including a longitudinal frame comprising a pair of bars secured in spaced relation, and a pair of holding plates having their upper edges bent in U-shaped formation and arranged for resilient engagement with the upper edges of the frame, one of said plates having a pair of spaced openings formed therethrough and the opposed plate having a pair of sleeves secured thereto in engagement with the openings, the said sleeves being adapted to engage the openings of a blade.

3. A blade holder comprising a frame having a vertically arranged recess formed in its forward portion, and blade holding plates adapted to be inserted in the recess in the frame having the upper edges thereof bent for resilient connection with the frame, and the intermediate portions of the plates being formed to firmly secure razor blades therebetween in suitable stropping position.

4. A blade holder comprising a frame formed of a pair of longitudinal bars, spacing blocks arranged between the end portions and intermediate portions of the bars, means for securing the said bars and lugs in position, the said frame thus forming a blade holder formed in the forward portion, and blade holding plates having their upper edges bent for resilient engagement with the frames, one of the said plates having openings formed therethrough and the opposite plate having transversely projecting sleeves engageable with the openings for firmly supporting a razor blade in proper stropping position.

5. A blade holder comprising a frame

- formed of a pair of longitudinal bars secured in spaced arrangement, and a pair of blade holding plates having their upper edges bent in **U**-shaped formation for resilient engagement with the frame bars, the intermediate portions of the said plates having longitudinal rectangular formed openings adapted to engage the reinforcing rib of a razor blade.
6. A device of the character described comprising a frame including a pair of spaced bars, spacing blocks arranged between the bars, and means for securing the said bars and blocks together, a pair of complementary holding plates having outwardly arranged flanges on their upper ends and outwardly beveled edges on their lower ends for supporting a razor blade in inclined position for re-sharpening, one of the said plates being provided with a pair of spaced openings, and the opposite plate carrying transversely extending sleeves for engagement with the openings, the said sleeves and openings being arranged to securely engage a razor blade.
7. A blade holder of the class described including a longitudinal frame comprising a pair of resilient bars secured in spaced relation, and a pair of holding plates having their upper edges bent in **U**-shaped formation and arranged for supporting a razor blade in inclined position and for resilient engagement of the plates with the upper edges of the frame, one of said plates having a pair of spaced openings formed therethrough and the opposite plate having a pair of sleeves secured thereto in engagement with the openings, the said sleeves being adapted to engage the openings of a blade.
8. A blade holder comprising a frame having a vertically arranged recess formed in its forward portion, and blade holding plates adapted to be inserted in the recess in the frame having the upper edges thereof bent for resilient connection with the upper edges of the frame bars, the said plates and the frame bars being arranged in a **V**-shaped formation to provide a bevel support for razor blades, and the intermediate portions of the plates being formed to firmly secure razor blades therebetween.
9. A blade holder comprising a frame formed of a pair of longitudinal bars, spacing blocks arranged between the end portions and intermediate portions of the bars, means for securing the said bars and blocks in position, the said frame thus forming a blade holder formed in the forward portion, and blade holding plates having their upper edges bent for resilient engagement with the frames, the said plates and the frames being arranged in a **V**-shaped formation to provide bevel support for a razor blade, one of the said plates having openings formed therethrough and the opposite plate having transversely projecting sleeves engageable with the openings for firmly securing a razor blade therebetween.
10. A blade holder comprising a frame formed of a pair of longitudinal bars secured in spaced arrangement, and a pair of blade holding plates having their upper edges bent in **U**-shaped formation to provide outwardly arranged resilient flanges, the intermediate portions of the said plates having longitudinal rectangular formed openings adapted to engage the reinforcing rib of a razor blade.

In testimony whereof I affix my signature.

JOHN HAVRAN.
